UNITED STATES PATENT OFFICE

104,405

DESIGN FOR A KNITTED TWO-PIECE DRESS

Daniel Rheinauer, New York, N. Y., assignor to
New York Knitting Mills, Inc., New York, N. Y.,
a corporation of New York

Application July 11, 1936, Serial No. 63,785

Term of patent 7 years

To all whom it may concern:

Be it known that I, Daniel Rheinauer, a citizen of the United States, residing at the Borough of Manhattan, in the city, county, and State of New York, have invented a new, original, and ornamental Design for a Knitted Two-Piece Dress, of which the following is a specification, reference being had to the accompanying drawings, forming part thereof.

Fig. 1 is a front view of a knitted two-piece dress, showing my new design.

Fig. 2 is a rear view of the top portion of the dress.

Fig. 3 is a rear view of the skirt portion of the dress.

The characteristic features of my design reside in the arrangement of contrasting ribbing in the body of the dress and in the terminal portions thereof, the diagonal integrally knit ribbing meeting without seams at the middle of the front and

back of both the sweater and the separate skirt comprising the dress, the sweater having a closed neck surrounded by a knitted ribbed collar, the skirt terminating at its bottom edge in a narrow horizontally chain-knit band, the diagonal ribbing in the sweater being inclined in directions substantially at right angles to the directions of the diagonal ribbing in the corresponding sides of the skirt, the lowermost waist portion of the sweater being provided with vertical relatively narrow ribs, the sleeves of the sweater being diagonally ribbed in a differently inclined direction from the adjacent diagonal ribbing of the sweater, and the sleeves terminating in relatively narrow ribs arranged angularly to the diagonal ribbing of the body of the sleeves.

I claim:

The ornamental design for a knitted two-piece dress, as shown and described.

DANIEL RHEINAUER.
